FOOTBALL CARD GAME

Sidney Katz, Boston, Mass.

Application December 24, 1935, Serial No. 56,098

3 Claims. (Cl. 273—152)

This invention relates to game apparatus, and more particularly to apparatus in the form of cards for playing the game of football.

An object of this invention is to provide a deck of cards together with rules for playing of the game of football, the cards being so constructed and designed and the rules being of such a character that substantially all of the plays used in the game of football may be used 10 in the card game.

Another object of this invention is the provision of a deck of cards and rules for playing of the game whereby an element of chance as well as skill in the choice of plays is inserted into 15 the game, while at the same time providing an exceedingly simple game which is preferably played by two persons.

In game apparatus heretofore available for the playing of the game of football the apparatus and rules for playing the game were of such a complicated nature that it was exceedingly difficult to play the game in the proper manner, and it is to provide a relatively simple game apparatus in the form of a deck of cards and rules 20 for the playing of the game so that the game can be played in a relatively rapid manner, and at the same time there is a sufficient element of chance together with an element of skill in the selection of the proper plays so that the game 25 may be played by persons of various ages with equal facility.

With the foregoing and other objects in view, the invention will be more fully described hereinafter, and will be more particularly pointed out 30 in the claims appended hereto.

In the drawings, wherein like symbols refer to like or corresponding parts throughout the several views,

Figure 1 is a plan view of one of the "Gain" 40 cards embodied in a game apparatus constructed in accordance with an embodiment of this invention.

Figure 2 is a plan view of one of the "No gain" cards.

Figure 3 is a plan view of one of the "First down" cards.

Figure 4 is a plan view of one of the "Loss" or penalty cards.

Figure 5 is a plan view of a "Touchdown" card.

Figure 6 is a plan view of one of the "Holding" or penalty cards.

Figure 7 is a plan view of one of the "Off-side" or penalty cards.

Figure 8 is a plan view of one of the "Fumble" or penalty cards.

Figure 9 is a plan view of another of the "Holding" or penalty cards.

Figure 10 is a plan view of another of the "Off-side" or penalty cards.

Figure 11 is a diagrammatic view of the playing field which may be optionally used with this game.

Referring to the drawings, and first to Figure 1, the numeral 15 designates a card of suitable size, preferably rectangular in plan, which is provided in the body thereof on the face or playing side thereof with a figure 16 simulating a football player in the act of kicking a football. 15

The card 15 is provided adjacent each corner with a numeral 17, and preferably there are eighteen cards of this particular type or character with each card bearing different numerals indicative of yards gained, and these numerals 20 are as follows: 1, 2, 3, 4, 5, 6, 7, 8, 9, 10, 15 and 20. It will be understood that each card bears four like numerals. Between one pair of numerals 17 and at one end of the card 15, there is the legend Gain and designated by the numeral 18. At 25 the other end of the card 15 and between the other pair of numerals 17 there is the legend Incomplete and designated by the numeral 19. The card 15 also has along one side thereof and adjacent the Gain end thereof the word Rush 30 which is indicated by the numeral 20. Diagonally opposite from the word Rush and at the opposite side or edge of the card 15 there is the legend or word Pass, designated by the numeral 21. 35

In Figure 2 there is shown another type of card which may be used for either a Rush or Pass, the card 22 having similar side legends 20 and 21. Between the numerals 23 at the corners of this card 22 there is the legend No gain, designated by the numeral 24, and this legend No gain is at the end of the card adjacent the word Rush, whereas the other or Pass end of the card 22 has the legend Complete between the corner numerals, this latter legend being shown at 25. 40 45 There are eight No gain cards, and the numerals at the corners thereof are as follows: 1, 2, 3, 5, 6, 8, 9, and 10.

Figure 3 shows a further card 26 provided with corner numerals 27, and these cards 26 are also 50 of the Rush-pass type. At the end of the card 26 adjacent the legend Rush and between the numerals 27 there is the legend First down which is designated by 28. The other or Pass end of the card 26 has the legend Intercepted, shown 55

at 29, which is positioned between the other pair of numerals 27. There are two of these First down-intercepted cards, and one card bears the numerals "8" while the other card bears the numerals "9".

The card 30 shown in Figure 4 has corner numerals 31, and this card 30 is of the Rush-pass type. A legend 32 or the word Loss, is disposed between the pair of numerals 31 at the 10 Rush end of the card 30, and a legend 33 in the form of the word Intercepted is between the other pair of numerals 31 at the opposite end of the card. There are five of these Loss-intercepted cards, and the corner numerals 31 are: 15 3, 4, 5, 6, and 7.

Figure 5 shows another card 34 of the Rush-pass type which bears corner numerals 35, the corner numerals on this type of card being "10". The legend or word Touchdown shown at 36 is disposed between one pair of numerals 35 at the 20 Rush end of the card 34, and the legend or word Intercepted, shown at 37, is at the Pass end of the card. There is only one Touchdown card in the entire deck.

25 A pair of penalty cards 38 and 39 are shown in Figures 6 and 9, respectively. The card 38 bears the character O at each corner, and at diagonally opposite corners bears the legend Penalty, shown at 40. The card 38 also has the 30 legend or word Holding, shown at 41, at each end thereof and between each pair of characters "O", the character "O" indicating the offensive team. The card 39 is similar in all respects to the card 38, with the exception that the corner 35 characters are D, shown at 42. The character "D" designates the defensive team in the playing of the game.

A second pair of penalty cards are shown in Figs. 7 and 10. The numeral 43 designates the 40 corner characters "O" of card 44 shown in Fig. 7, and the numeral 45 designates the character of the penalty, which in this case is Off-side, and this legend appears at opposite ends of the card 44 and between each pair of characters "O". 45 Card 46 shown in Fig. 10 is similar in all respects to card 44, with the exception of the corner characters 47, which are "D". With these cards 44 and 46, as with the cards 38 and 39, the characters "O" and "D" designate the 50 offensive and defensive teams, respectively.

In Figure 8 there is shown a card 48 of the Rush-pass type, and these cards 48 bear corner numerals 49, the corner numerals of one card being 4 and the corner numerals of the other 55 card being 1. These cards 48 have a legend 50 adjacent one end and between the numerals 49 at the Rush end of the card, the legend 50 being characterized by the word Fumble. The opposite or Pass end of the cards 48 bear a legend 60 51 in the form of the word Complete.

Figure 11 shows diagrammatically a playing field of the usual size, the transverse lines indicating the 10-yard markers. A diagram of this character may be optionally used with this game, 65 and if desired additional yard markers may be shown.

Rules

The rules of the game are as follows:

70 The initial offensive and defensive teams may be chosen in any suitable manner, as by the flip of a coin, and when sides have been chosen, the offensive player shuffles the cards, and play starts with the kick-off which is on the forty-yard line. 75 The defensive player or opponent may cut the

shuffled deck, and then the offensive player who is kicking off draws six cards from the top or middle of the deck, which is placed in inverted position. The corner numerals of these six cards are then added up and the sum total of these 5 numerals indicates the total yardage of the kick-off. In the event any penalty cards, which do not bear corner numerals, are drawn at the kickoff, the player may draw other cards in their place.

After the total of the corner numerals has 10 been ascertained at the kickoff, the six cards are then scanned and in the event the legend on the Pass end of each card is the same, that is, either Complete, Incomplete, or Intercepted, then the receiver of the ball is given credit for running 15 back the ball for a touchdown. If the first six number bearing cards are not alike on the Pass end thereof the receiver of the ball begins play at the point indicated by the total length of the kickoff. After the ball has been kicked off the 20 offensive player must before drawing any cards from the deck, which is shuffled after each play, name the character of the play.

The offensive player, having stated that the next play is to be a punt, draws one card from 25 the deck, and if this card is not a penalty card he then draws five more cards. The yardage of the punt is determined by the total of the corner numerals on the drawn cards. If the first card drawn is a penalty card the yardage for the 30 penalty is taken, and then six more cards are drawn.

The penalty for holding is fifteen (15) yards, and the penalty for off-side is five (5) yards.

Blocked kick.—If five of the six number bearing cards drawn for the punt read the same on the Pass side then the kick has been blocked, and the ball is given to the opposing player or team on the line of scrimmage of that particular play.

Punts run back for touchdown.—If all six 40 cards drawn for the punt read the same on the Pass side, then the punt has been run back for a touchdown.

Rush rules.—Player having designated that he desires to rush the ball draws one card, and 45 the result of the Rush will be indicated on the Rush side of the card. The total yardage gained or lost is indicated by the corner numeral of the drawn card. As an example, player having stated that he will rush the ball, draws one card 50 which on the Rush side thereof bears the legend Gain. The total yardage gained is indicated by the numeral in the corner of the card.

Fumble rule.—If player, having stated that he desires to Rush, should draw a Fumble card he 55 automatically loses the ball on the line of scrimmage to the opposing side. In this instance the numerals in the corners of the Fumble card are disregarded.

No gain rule.—If player, having stated that he 60 desires to Rush, should draw a No gain card, the numerals in the corners of the card should be disregarded and play resumed on the line of scrimmage.

First down rule.—Player who gains ten or 65 more yards, either by Rush, Pass, or Penalty, within five downs is given the right to a first down. Every play made is counted as a down, with the exception of penalties, and if a player has not made a gain of ten yards or more within 70 a series of five downs, he automatically loses the ball to his opponent on the line of scrimmage determined by the last down, unless he has chosen to punt on the last down. If player draws a First down card when intending to rush, the 75

corner numerals of this particular card are disregarded and the ball moved forward a sufficient distance to make the first down.

Pass rule.—Player, having called for a pass, draws one card from the shuffled deck, and the result of the pass will be determined on the Pass side of the card. If the card drawn indicates Incomplete on the Pass side thereof, a down is counted and no other card need be drawn. If a Complete card is drawn, player then draws two more cards, Penalty cards not included, and adds up the total numerals to indicate the yardage gained by the pass. If an Intercepted card is drawn, then the pass has been intercepted by the opponent, and in this case the player making the pass shall draw two more cards and add up the corner numerals to indicate the distance away from the original line of scrimmage where the pass was intercepted, and the player or team intercepting the ball starts play from that point. Passes cannot be intercepted behind the goal line unless intercepted for a touchdown, which is then run back for the entire length of the field. An intercepted pass which is not a touchdown is given to the opposing player on the line of scrimmage.

Touchdown pass rule.—If the first Pass card indicates a completed pass, and if the subsequently drawn two cards also read Complete, then the pass is good for a touchdown for the offensive player.

Touchdown by interception.—If all three cards drawn by the offensive player read Intercepted on the Pass side, then the intercepting player has run the ball for a touchdown.

Point after touchdown.—Player, having made a touchdown draws one card from the shuffled deck, and if the corner numeral is "8" or above, the kick is good and one point counted. If the numeral in the corner is less than "8" the kick is no good. If a Penalty card is drawn bearing the corner character "D", the kick is also good, but if the Penalty card shown a character "O", then the kick is no good.

Field goal rule.—Players who are within the opponent's twenty-five (25) yard line are eligible to try for a field goal, that is the offensive player may designate the next play as a try for a field goal. On this occasion the player draws one card, and if the corner numeral is "8" or higher, the kick is good and three (3) points are given for the goal kick. If the corner numeral is less than eight "8" the kick is no good. Having called for a field goal, if player draws a Penalty card, the penalty on the side indicated by the corner character is enforced, and if player so desires and the "Down" rule permits, either a field goal may be elected as the next play, or any other play may be called. After the ball has been kicked for a field goal, if the kick is no good, the ball is given to the opposing side on the twenty (20) yard line. If kick is good ball is kicked off by team that made goal from their own forty (40) yard line.

65 Scores

Touchdown	6 points
Point after touchdown	1 point
Field goal	3 points
Safety or touchback	2 points

70 In order to count a score, the ball must cross over the goal line, or in other words if an offensive player is on the two (2) yard line, and if the Gain card bears the numeral "2", then the ball is moved to the goal line, but another card

must be drawn and another down taken. Assuming the above status and the play being made on the fifth down, then the ball goes over to the opposing side on the goal line. This rule also applies for a touchback.

Where a Penalty card is drawn against the defensive side, the penalty is taken against the defensive side, and the ball moved as far as possible toward the goal line, but if the penalty is more than the distance to the goal line, then the ball is placed on the goal line, and a further try must be made for a score.

The scoring or position of the ball on the playing field can be indicated by at least one of two ways. If the diagram shown in Fig. 11 is used an article of some sort may be used to simulate a football and this article moved back and forth in accordance with the plays. If the diagram of the field is not used, then the position of the ball may be shown and the down number shown as follows: A letter, as for example "Y" may be used to designate one player or team, and a second letter, such as "H" used to designate the other player or team. Now assuming that "Y" is the offensive player, "H" is the defensive player, the ball is on the forty-five yard line of "H" and it is first down for "Y". This condition may be set down as follows:

$$\begin{matrix} Y & 1 \\ \hline H & 45 \end{matrix}$$
 30

If "Y" elects to rush the ball, and the yardage count is three (3) yards, then the status will be as follows:

$$\begin{matrix} Y & 1 & 2 \\ \hline H & 45 & 42 \end{matrix}$$
 35

The bottom character denotes the position of the ball, that is whether it is in the territory of "H" or "Y", and the top character denotes the offensive player, whereas the top number indicates the down number and the lower number indicates the yard marker or position of the ball.

It will be obvious that an exceedingly interesting and at the same time simple game has been provided for the playing of the game of football so that various kinds of plays may be called in the same manner as such plays are called in the actual playing of the game on the gridiron.

I do not wish to be restricted to the size, form and proportions of the various cards, and obviously changes could be made in the construction herein described without departing from the spirit of the invention, it being only necessary that such changes fall within the scope of the appended claims:—

What is claimed is:

1. A football game apparatus comprising a deck of cards including a series of movement cards, certain of said cards having a numeral in each corner, a movement indication at each end between each pair of numerals, with the movement indication on one end of each card contradistinguished from the movement indication on the other end of the card, and each of said cards having a play indication on each edge at diametrically opposed corners, and a series of penalty cards provided with characters indicative of the ball carrier at each corner and also provided with a penalty indication adjacent each end and between said characters.
2. A football game apparatus comprising a deck of cards including a series of movement cards, each card having a numeral in each

- corner, a movement indication at each end between each pair of numerals with the movement indication on one end of each card contradistinguished from the movement indication on the other end of the card, and each of said cards having a play indication on each edge at diametrically opposed corners, a series of loss cards, and a series of penalty cards provided with characters indicative of the ball carrier at each corner and also provided with a penalty indication adjacent each end and between said characters.
5. A football game apparatus comprising a deck of cards including a series of movement cards, each card having a numeral in each corner, a movement indication at each end between

each pair of numerals with the movement indication on one end of each card contradistinguished from the movement indication on the other end of the card, and each of said cards having a play indication on each edge at diametrically opposed corners, the play indication on one edge being contradistinguished from the play indication on the other edge of the card, a series of penalty cards provided with characters indicative of the ball carrier at each corner and also provided with a penalty indication at each end and between said characters, a series of loss cards, and at least one touchdown card, said loss cards and said touchdown card each having a numeral in each corner. 15

SIDNEY KATZ.
